(57) CLAIM

The ornamental design for a retractable sunshade, as shown and described.

DESCRIPTION

FIG. 1 is a first perspective view of a retractable sunshade showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a first perspective view of another state of the retractable sunshade thereof; and,

FIG. 10 is a second perspective view of another state of the retractable sunshade thereof.

The dashed or broken lines shown in the drawings depict portions of the retractable sunshade which the design is embodied that form no part of the claimed design.
